UNITED STATES PATENT OFFICE.

WILLIAM G. WILSON, OF WEST BRIGHTON, NEW YORK.

TRACK CONSTRUCTION.

1,040,082.

Specification of Letters Patent. Patented Oct. 1, 1912.

Application filed March 26, 1912. Serial No. 636,445.

To all whom it may concern:

Be it known that I, WILLIAM G. WILSON, a citizen of the United States, residing at West Brighton, county of Richmond, and State of New York, have invented a new and useful Improvement in Track Construction, of which the following is a specification.

This invention relates to an improvement 10 in track construction, and it has for its main object the production of a track possessing all the resiliency of a track of the ordinary construction in which steel rails and wooden ties are used, and possessing, 15 further, devices for preventing spreading or overturning of the rails.

The invention consists in certain constructions and combinations which will be hereinafter fully described, and then specifically 20 set forth in the claims hereunto appended.

In the accompanying drawings, which form a part of this specification and in which like characters of reference indicate the same or like parts, Figure 1 is a perspective view of a track constructed in accordance with the invention, Fig. 2 is a detailed side elevation of a part of the structure shown in Fig. 1, Fig. 3 is an enlarged fragmentary detail view, partly in section, 25 illustrating the method of insulating the rails, and Fig. 4 is a fragmentary cross-sectional view of one of the rails and rail spacing devices.

In carrying the invention into effect, there 30 is provided a pair of rails 1, and a series of wooden ties 2 of the ordinary construction, the wooden ties 2 being adapted to support the rails and to be in turn supported by the road-bed indicated at 3 in Fig. 2. 35 The device so far described differs in no way from an ordinary track.

For the purpose of preventing the rails from spreading or overturning from any cause, there are provided a plurality of rail 40 spacing members, the number of rail spacing members being less than the number of ties supporting the rails. These rail spacing members underlie and are supported by the rails, but are not supported by the road-bed, as is clearly shown in Fig. 2. The 45 particular type of rail spacing member shown in the drawings includes end-sections 4 and 5, and a rigid bar 6 bolted to and connecting said end-sections. The end section 4 comprises two parts one of which has a projection 7 overlying one side of the

base of the rail. The other part has a projection 8 overlying the opposite side of the base of the rail. These two parts lie side by side and are rabbeted to receive the 50 end of the rigid bar 6. The two parts are held together by bolts 9, 10 and 11. The bolts 10 and 11 are respectively insulated from the section 4 and the rigid bar 6 by means of non-conducting sleeves 12 and 13. 55 The bar 6 is insulated from the parts of the end section 4 by non-conducting plates 14 and 15. The object of this insulation is to prevent interference with the electric signaling system in which the rails are used as 60 conductors. The end section 5 is similar in all respects to the end section 4 just described, and it is therefore deemed unnecessary to specifically describe said section 5.

It will be readily understood, particularly 65 upon inspection of Fig. 2, that the presence of the rail spacing members interferes in no way with the resiliency of the track as a whole, but that it will prevent the rails from spreading or overturning from any 70 cause, particularly when the spikes holding the rails to the ties become loosened.

Changes and variations may be made in the structure by means of which the invention is carried into effect. The invention, 75 therefore, is not to be limited to the precise details of the structure shown and described.

What is claimed is:

1. A railway track comprising a pair of rails, a series of wooden ties supporting the rails and resting upon the road bed, a plurality of rail spacing members underlying and supported by the rails and unsupported by the road bed, each of said spacing members being made up of end sections and a middle section horizontally bolted together, said end sections having projections overlying both sides of the base of both rails.

2. A railway track comprising a pair of 190 rails, a series of wooden ties supporting the rails and resting upon the road bed, a plurality of rail spacing members underlying and supported by the rails and unsupported by the road bed, each of said members being 195 made up of end sections and a rigid middle section horizontally bolted together and insulated one from the other, said end sections having projections overlying both sides of the base of both rails.

3. A spacing member for the rails of a railway track comprising a rigid bar, and

a pair of oppositely disposed end sections horizontally double-bolted one to each end of the rigid bar, each of said end sections consisting of a pair of sister bars adapted to underlie the base of a rail and having oppositely disposed projections adapted to overlie both sides of the base of a rail.

4. A spacing member for the rails of a railway track comprising a rigid bar, and 10 a pair of oppositely disposed end sections, the adjacent ends of the end sections being rabbeted to receive the ends of the rigid bar and being insulated from and horizon-

tally double-bolted to said bar, each of said end sections consisting of a pair of sister bars, adapted to underlie the base of a rail and having oppositely disposed projections adapted to overlie both sides of the base of a rail.

In testimony whereof, I have signed my name to this specification in the presence of two subscribing witnesses.

WILLIAM G. WILSON.
